[57] **CLAIM**

The ornamental design for a window cleaner with detachable wiping portion, as shown and described.

DESCRIPTION

FIG. 1 is a perspective view showing the handle, right side and one end of our design for a window cleaner with detachable wiping portion, said detachable wiping portion being shown in the assembled position;

FIG. 2 is a right side elevational view thereof; the left side elevational view is a mirror image of FIG. 2;

FIG. 3 is a top plan view thereof;

FIG. 4 is a bottom plan view thereof with the wiping portion in the assembled position; and,

FIG. 5 is an elevational view from one end thereof; the opposite end is a mirror image of FIG. 5.
